COMBINATION TABLE AND IRONING BOARD

William Nelson, New York, N. Y.

Application June 13, 1935, Serial No. 26,499

3 Claims. (Cl. 68—10)

This invention relates to a combination table and ironing board.

The primary object of the invention is to provide a table with an ironing board that may be extended and retracted with respect to the table and is an improvement on my Patent 1,468,728 granted September 25, 1923.

Another feature of the invention is the provision of extension leaves on the table which may be extended and retracted into the table without interfering with the operation of the ironing and that may be manipulated with ease and dispatch.

With the foregoing and other objects in view the invention consists of a novel construction, combination and arrangement of parts as will be hereinafter more specifically described and illustrated in the accompanying drawings wherein is disclosed and embodiment of the invention, but it is to be understood that changes, variations and modifications may be resorted to without departing from the spirit of the claims hereunto appended.

In the drawings wherein like reference characters denote corresponding parts throughout the several views:

Figure 1 is an end elevation of the table constructed in accordance with the present invention and showing the parts in the retracted relation.

Figure 2 is a front elevation thereof showing the ironing board in extended position.

Figure 3 is a detailed vertical sectional view taken substantially on line 3—3 of Figure 2.

Figure 4 is a top plan view of the table showing the ironing board in extended position and with the permanent top and the extension leaves removed.

Referring to the drawings in detail, numeral 7 indicates upright legs at the four corners of the table. In the center of the front legs 7 there are formed transverse grooves 8 and on the rear legs there are similar transverse grooves 9 on the inner edges thereof. The grooves 8 and the grooves 9 extend downwardly into the legs from the upper ends thereof to slidably support the props on the extension leaves as will hereafter appear. There is an apron or skirt around the intermediate portion of the table to simulate a cabinet and this apron is formed of end walls 10 secured at their ends to the legs. There is also a rear side wall 11 secured at its opposite ends to the legs and a front side wall 12 secured at its ends to the legs. The front side wall 12 does not extend

to the top of the legs but the rear side wall and the end walls extend to the tops of the legs. All of these walls terminate materially above the bottoms of the legs.

Interiorally of the table there are longitudinally spaced cross braces four in number indicated at 13, 14, 15, and 16. These braces are secured at their rear ends to the rear side wall 11 and at their front ends to the front side wall 12. The tops of the braces are below the edges of 10 the end and rear side walls. Braces 13, 14 and 15 have their upper edges in the same horizontal plane while brace 16 extends above the plane of the other braces. At the forward portion, the cross brace 16 is cut away to support an intermediate portion of a longitudinal platform 17. This platform 17 has one end secured to one leg 8 and the end wall 10, while the other end is secured to the upper edges of the braces 14, 15. This platform 17 is disposed horizontally, and provides a 20 support for the counter-support on the ironing board as will hereafter appear. The cross braces 15, 16 also provide a sliding support for a drawer 18 that slides into and out of an opening 19 in the front wall. On the confronting faces of the 25 braces 15, 16 are the usual cleats 18' to slidably support the drawer 18. Extending longitudinally across the center is a relatively narrow board that is called the anchor plate 20 and the opposite ends of this anchor plate is secured to the top edges 30 of the end walls 10. Superimposed upon and secured to the anchor plate 20 is the stationary or permanent table top 21. Since the permanent table top 21 is secured to the anchor plate there is a space or pocket between the upper edges of 35 the end and side walls into which extends and retracts the extension leaves 22, 23 one on each side of the anchor plate. On each end of the front leaf 22 is a pair of inwardly directed guide props 24 which slide in the grooves or notches 8. Adjacent the ends of the rear leaf 23 are similar guide props 25 which slide in the notches or grooves 9 in the rear legs. The inner ends of the guide props overlap as shown in Figure 3 of the 40 drawings when the extension leaves are retracted under the permanent table top. The inner ends of the guide props project free of the inner edges of the respective extension leaves and the upper edges of the props decline inwardly. A portion of the bottom edge of each prop is curved as at 45 26 for approximately the width of the respective extension leaves, while the remaining bottom edge is straight and inclined as at 27 from the curved portion to the free end of the respective 50 55

props. The curvature 26 and the straight inclined portion 27 of the bottom edges of the respective props permit the extension leaves to be pulled outwardly from under the permanent table top and in being pulled outwardly they rise substantially to the level of the permanent table top 21 as indicated in dotted lines in Figure 1 of the drawings.

Adjacent one end of front wall 12 there is an opening 28 in which slides transversely an elongated ironing board support block 29. Throughout the length of the block 29 there is a groove 30 that embraces and rides on cross brace 13 whereby the block is slidably supported. Extending longitudinally of the table is an ironing board 31 one end of which is secured to the upper face as at 32 of the outer portion of the block 29. The other end of the ironing board is free of support. The ironing board 31 extends at right angles to the block 29 and on the rear end of the block is secured as at 33 the one end of a counter support 34. This counter support is free at one end and is adapted to rest upon the platform 17 when the ironing board 31 is in the extended position shown in Figure 4 of the drawings. In the retracted position the free portions of the counter-support 34 rest upon the upper edge of cross brace 16 and slides thereon. To close the space between the upper edges of front wall 12 and the bottom of extension leaf there is a gate or shutter 35 hinged to swing edge-wise on dowel pins 36 and the outer ends of the dowel pins are seated in the inner portions of the legs 7. The outer face of the ironing board supporting block 29 has a knob 37 thereon to manipulate the block and the gate or shutter 35 has a knob 38 thereon for the same purpose as has also the drawer 18 a like knob 39.

It will thus be seen that by raising the gate or shutter 35 the ironing board 31 may be moved into or out of the interior of the table as desired by simply pulling or pushing on the knob 37 on the front face of the block 29. In the retracted position, the gate 35 covers the front edge of the ironing board and in the extended position the gate covers the forward edge of the counter-support 17 as will be understood by referring to Figure 3 of the drawings.

Having thus described the invention, what is claimed as new is:

1. A cabinet table comprising upright legs at each corner, end and side walls secured to the legs, spaced interior cross braces, a longitudinal platform secured at one end to a cross brace and at the other end to one of the legs, a transverse support block formed with a groove embracing

one of the cross braces and slidable thereon, an ironing board secured at one end to one end of the block and free at the other end, a longitudinal counter-support secured at one end to the other end of the block adapted to rest on the platform when the ironing board is extended and on one of the braces when the ironing board is retracted. 5

2. A cabinet table comprising a table top supported on legs and having a skirt secured to the upper portions of the legs, said skirt including 10 sides and ends for the cabinet table providing an interior compartment, and one of the sides terminating below the table top to furnish an opening for the compartment; the combination with the aforesaid elements of spaced cross braces secured 15 to the sides of the skirt within the compartment, a longitudinal platform within the compartment adjacent the opening and supported by certain of the braces, a transverse supporting block equipped with a groove embracing one of the cross 20 braces and slidable thereon, an ironing board movable through the opening secured at one end to the outer end of the block and free at the other end which is adapted to rest on the platform when retracted in the compartment, a longitudinal 25 counter-support secured at one end to the inner end of the block adapted to rest on the platform when the ironing board is extended and also to rest on one of the braces when the ironing board is retracted. 30

3. A cabinet table comprising a table top supported on legs and having a skirt secured to the upper portions of the legs, said skirt including sides and ends for the cabinet table providing an interior compartment, and one of the sides 35 terminating below the table top to furnish an opening for the compartment; the combination with the aforesaid elements of spaced cross braces secured to the sides of the skirt within the compartment, a longitudinal platform within the 40 compartment adjacent the opening and supported by certain of the braces, a transverse supporting block equipped with a groove embracing one of the cross braces and slidable thereon, an ironing board movable through the opening secured at one end to the outer end of the block and free at the other end which is adapted to rest on the platform when retracted in the compartment, a longitudinal counter-support secured at one end to the inner end of the block adapted to rest on the 45 platform when the ironing board is extended and also to rest on one of the braces when the ironing board is retracted, and a gate closure pivoted to corresponding legs to close the opening in the side wall of the skirt. 55

WILLIAM NELSON.
